UNITED STATES PATENT OFFICE

DARIUS E. SHRAUGER, OF ATLANTIC, IOWA

WINDOW HALF SCREEN

Application filed February 4, 1929. Serial No. 337,328.

The object of my invention is to provide a window half screen of simple, durable and comparatively inexpensive construction.

A further object of my invention is to provide a screen structure consisting of a screen covered frame and a pair of guide and supporting tracks, the parts being arranged relative to each other whereby the screen may be tipped relative to the guide tracks and easily withdrawn from them, this operation being performed from the inside of a building in which the window is mounted.

More particularly it is my object to provide a screen frame of novel construction whereby a screen covering may be applied thereto and stretched relative thereto in a convenient manner.

Another object is to provide in combination with a screen frame, a pair of guide tracks each one having a pair of flanges so arranged that a notch is formed between the flanges through which the screen frame may slide whereafter the screen frame may be swung to a position contacting with the flanges for thereby supporting the screen relative to the window.

Still a further object is to provide means for covering the notch between the flanges of the guide track to prevent the entrance of flies therethrough.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is an outside elevation of a window set in a building wall and illustrating my screen construction associated therewith, the lineal dimensions of various parts of the device being considerably reduced for conserving space on the drawings.

Figure 2 is an enlarged sectional view on the line 2—2 of Figure 1.

Figure 3 is a sectional view on the line 3—3 of Figure 1, illustrating the window screen in position for removal or insertion relative to the window frame.

Figure 4 is an enlarged sectional view on the line 4—4 of Figure 1 and

Figure 5 is a perspective view of the guide track for an edge of the window screen.

On the accompanying drawings I have used the reference numeral 10 to indicate generally the wall of a building or the like. A window frame including a sill 12 and side casings 14, is mounted in the wall 10. The side jambs of the window frame are indicated at 16.

The side jambs of an ordinary window frame construction, are each provided with a blind stop 18 and a parting bead 20. The lower rail of the upper sash of the window is indicated at 22 and the glass of the upper sash at 24. My window screen construction consists of a screen A and a pair of guide or supporting tracks B. The screen A consists of a substantially rectangular flat frame member 26 to which is secured adjacent each edge, a moulding member 28.

The rectangular frame member 26 may be formed of one sheet of metal having a rectangular opening cut through it, or may be built up of several strips of metal. The moulding members 28 are mitered at their ends as indicated in dotted lines in the lower right hand corner of Figure 1.

The rectangular frame member 26 and the moulding members 28, may be spot welded or otherwise secured together. The upper end of the rectangular frame member 26 is provided with a flange 30 adapted to coat with the lower rail 22 of the upper window sash.

A screen covering 32 is provided for the screen frame A and its peripheral edges are adapted to fit over the moulding members 28 and to be secured thereto by means of a rectangular moulding cover member 34. The moulding cover member 34 may be formed of four members mitered at their ends as shown in dotted lines in the lower right hand corner of Figure 1 and these mitered ends may be covered with corner pieces 36. The corner pieces 36 are spot welded or otherwise secured to the moulding cover member 34.

For securing the screen 32 between the moulding member 28 and the moulding cover 100

member 34, I provide screws 38 adapted to rotatably extend through openings in the screen cover members and to screw threadedly engage in openings in the moulding members 28.

It will be noted that the sides of the moulding members 28 and the moulding cover members 24, diverge toward the rectangular frame member 26 so that when the originally flat screen 32 is placed in position covering the moulding members 28, the moulding cover member 34 may then be positioned thereon for holding the screen 32 relative to the screen frame A.

The screws 38 when inserted in position, tend to stretch the screen 32 on its frame. The lower end of the screen frame A is provided with a handle 38.

For supporting the screen A, I provide a guide member B to be attached to each blind stop 18. Each member B consists of an attaching flange 40 and flanges 42 and 44 extending at right angles therefrom. The flange 40 is provided with openings 48 through which screws 50 may extend into the blind stop 18 for supporting the same relative thereto.

The flanges 42 and 44 are staggered relative to each other as clearly shown in Figures 2, 3, 4 and 5 of the drawings. A notch 46 is provided between the adjacent ends of the flanges 42 and 44. The flange 42 is adapted to contact with the inner surface of the screen A and the flange 44 with the outer surface thereof.

A slide plate 52 is hingedly connected with the upper end of the flange 44. The flange 44 is depressed as indicated at 54 to receive the lower end of the slide plate 52 when in the position shown in Figures 1 and 2. At the lower end of the track B, a strip of metal 56 is provided which has on it a flange 58 whereby a socket-like receiving device is formed, the purpose of which will hereinafter be fully described.

45 *Installation and operation of my device*

In the installation of my device, the track members B are secured in position on the blind stops 18 as clearly shown in the drawings. The side edges of the screen frame A may now be positioned on the slide plates 52 and the screen frame A slid upwardly to the position shown in Figure 3.

The screen frame A is narrower than the distance between the blind stops 18 of the window frame whereby the screen frame may be caused to assume the position shown in Figure 3 from the inside of the window. After assuming the position shown in Figure 3, the screen frame A may be swung in the direction of the arrow 60 whereby the outer surface of the moulding members 28 of the screen frame A may engage the flanges 44 and the inside surfaces of the rectangular

frame member 26, may engage the flanges 42 as shown in Figure 2 of the drawings.

The screen frame A may now be moved downwardly so that the lower end thereof is received in the sockets formed by the flanges 58 on the members 56 whereby the screen is properly supported relative to the window frame.

The overall width of the screen frame A is preferably less than the distance between the flanges 40 of the track members B so that either the screen frame or the parts of the building may expand or contract relative to each other and yet the parts may properly cooperate with each other to provide a fly-tight covering for the portion of the window opening below the rail 22 of the upper sash.

The slide plates 52 besides serving the function of a convenient rest for the screen frame A as it is installed or removed relative to the window frame also serves the purpose of closing the notch 46 between the adjacent ends of the flanges 42 and 44 especially when the screen frame A is considerably narrower than the distance between the flanges 40 of the track members B.

The extension 30 on the rectangular frame member 26 serves to coact with the rail 22 of the lower sash of the window to prevent the entrance of flies and being made of considerable width, allows for considerable variation in the dimensions between the rail 22 and the sill 12.

The handle 38 is provided for convenience in installing or removing the screen frame A relative to the guides B. It will be obvious that any type of screen frame may be associated with the track members B and yet cooperate therewith in a similar manner. Wooden frames, for instance, might be used and the flanges 42 and 44 staggered to a greater degree for properly fitting such frames.

Although I have illustrated my screen structure as applied to the lower half of a window opening in which vertically slidable sashes are arranged, it is obvious that it may be designed for the full length of a window frame having swinging windows or the like.

In either event the invention would operate in the same manner.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a screen construction for windows, a screen frame, means for supporting the same comprising guide tracks at the sides of said windows each guide track including a pair of flanges arranged end to end but offset from each other, the space between the offset ends

- allowing the screen frame to pivotally and slidably coact with the tracks for removal and insertion of the screen relative to the window.
5. 2. In a screen construction for windows, a screen frame and means for supporting the same comprising guide tracks at the sides of said windows and means whereby the screen frame is pivotally and slidably mounted relative thereto for removal of the screen from the window, said means including slide plates pivoted to the guide tracks and adapted to have the screen frame slide thereon.
10. 3. In a screen construction for windows, a screen frame and means for supporting the same comprising guide tracks at the sides of said windows, said guide tracks having notches whereby the screen frame is pivotally and slidably mounted relative thereto for removal of the screen from the window and slide plates pivoted to the guide tracks and adapted to have the screen frame slide thereon and to close said notches against the entrance of flies.
15. 4. In a device of the character disclosed, for use with a wall having a window opening therein, a screen frame of less width than said window opening and means for mounting the same comprising guide tracks secured to the sides of said window opening, each guide track having a flange to engage a portion only of the height of said screen frame and a second flange to engage another portion only of such height and a plate hinged to one of said flanges to engage a portion of said rail between said two first mentioned portions.
20. 5. In a device of the character disclosed, for use with a wall having a window opening therein, a screen frame of less width than said window opening and means for mounting the same comprising guide tracks secured to the sides of said window opening, each guide track having a flange to engage a portion of a side rail of said screen frame and a second flange to engage another portion of said side rail and a slide plate to engage a portion of said rail between said two first mentioned portions, said slide plate being pivoted to one of said flanges.
25. 6. In a device of the character disclosed, for use with a wall having a window opening therein, a screen frame of less width than said window opening and means for mounting the same comprising guide tracks secured to the sides of said window opening, each guide track having a flange to engage a portion only of the height of said screen frame and a second flange to engage another portion only of such height, such portions being on opposite sides of the screen frame, a slide plate to engage a portion of said rail between said two first mentioned portions and means for engaging one end of said screen frame to prevent pivotal movement of

and thereby retain the same against said flanges.

7. Supporting means for a screen frame comprising a member having a pair of flanges positioned substantially end to end and in staggered position with respect to each other and each adapted to engage different longitudinal portions and opposite sides of a screen frame.

8. Supporting means for a screen frame comprising a member having a pair of flanges positioned substantially end to end and in staggered position with respect to each other, each flange being adapted to engage a different longitudinal portion and an opposite side of a screen frame from the other flange and a socket at one end of one of said flanges for receiving an end of said screen frame for preventing pivotal movement thereof on an axis adjacent the place where the flanges are staggered and to thereby retain the screen frame against said flanges.

9. Supporting means for a screen frame comprising a member having a pair of flanges positioned substantially end to end and in staggered position with respect to each other and a slide plate pivotally supported on one of said flanges.

10. Supporting means for a screen frame comprising a member having a pair of flanges positioned substantially end to end and in staggered position with respect to each other and a slide plate supported on one of said flanges, said slide plate being pivotally mounted relative to the flange on which it is supported.

11. Supporting means for a screen frame comprising a member having a pair of flanges positioned substantially end to end and in staggered position with respect to each other, said flanges being adapted to engage different longitudinal portions of a side rail of said screen frame on opposite sides thereof and a clip at one end of one of said flanges to engage said screen frame to retain it in position with respect to said flanges.

Des Moines, Iowa, December 19, 1928.
